REFRIGERATION EXPANSION VALVE

Earnest J. Dillman and Franklyn Y. Carter, Detroit, Mich., assignors to Detroit Lubricator Company, Detroit, Mich., a corporation of Michigan

Application April 5, 1945, Serial No. 586,668

14 Claims. (Cl. 62—8)

1

This invention relates to new and useful improvements in expansion valves for controlling the flow of refrigerant and more particularly to such a valve which is operated in accordance with both the temperature and the pressure of the refrigerant.

In mechanical refrigeration systems of the compressor condenser type it has been customary to utilize an external pressure or equalizer line or conduit to convey pressure from the evaporator outlet to the valve operating pressure responsive member. It has also been customary to utilize a liquid charged power element having a feeler bulb or member to sense the temperature at the outlet of the evaporator to actuate the power element for operating the valve in accordance with temperature changes.

It is one object of this invention to provide an expansion valve responsive to both the temperature and the pressure adjacent the outlet of the evaporator without the necessity of using either the equalizer connection or the feeler bulb.

Another object is to provide a valve which will respond accurately to both temperature and pressure changes and control the flow of the refrigerant with a minimum of surging.

Another object is to provide a valve which is capable of commercial quantity production and which is of low cost construction.

The invention consists in the improved construction of parts to be more fully described hereinafter and the novelty of which will be particularly pointed out and distinctly claimed.

In the accompanying drawings, to be taken as a part of this specification, there are fully and clearly illustrated several preferred embodiments of the invention, in which drawings—

Figure 1 is a view of the expansion valve in side elevation and showing it operatively arranged in a diagrammatically illustrated refrigerant system;

Fig. 2 is a top plan view of the expansion valve showing its connecting conduits;

Fig. 3 is a view in section on the line 3—3 of Fig. 2;

Fig. 4 is a view in section on the line 4—4 of Fig. 2;

Fig. 5 is an enlarged detail view showing the inner connection of the valve operating rod or wire and the diaphragm;

Fig. 6 is an enlarged detail view of a modification showing means for equalizing pressure during stoppage of the compressor;

Fig. 7 is a top plan view of another form of thermostatic expansion valve having the invention;

Fig. 8 is a view in vertical section on the line 8—8 of Fig. 7;

Fig. 9 is a detail view in end elevation of the valve of Fig. 7;

Fig. 10 is a detail view in side elevation of the valve of Fig. 7 with parts broken away to show internal construction, and

Fig. 11 is an enlarged detail view of a modification showing means for anticipating flooding of the evaporator.

Referring to the drawings by characters of reference and particularly Figs. 1 to 5, the numeral 1 designates generally a motor driven compressor controlled in its cycle of operation by any of the well known devices. The compressor 1 discharges through a pipe or conduit 2 into the usual condenser 3 which feeds into a receiver 4 from which a pipe or conduit 5 which is the refrigerant liquid line connects as at 6 to the inlet 7 of the thermostatic expansion valve 8 which is shown as of the multiple type having outlet connections 9, 10 connected by pipes or conduits 11, 12 respectively to the inlets of evaporators or the multiple passes 13, 14 of an evaporator. The outlets of the evaporators 13, 14 are connected to a common refrigerant return or suction line or conduit 15 which is connected by the inlet fitting 16 to the pressure chamber 17 of the expansion valve. The chamber 17 is intercalated in the suction line and flow from the chamber discharges through an outlet fitting 18 having connected thereto the suction line or conduit 19 which connects into the suction side of the compressor 1.

The expansion valve 8 has a housing or body member which includes a cup-like casing 20 which forms the chamber 17 and has a substantially cylindrical side wall 21 open at its lower end. The upper end of the chamber 17 is closed by a casing end wall 22. Projecting from the opposite faces of wall 22 concentric with the chamber 17 there is a tubular member 23, see Fig. 4 having an external portion 24 and an internal portion 25 within the chamber 17. At the inlet end of the portion 24 which connects to the valve inlet 7, the hollow interior or bore of the portion 24 is enlarged as at 26 to provide a valve chamber. The outlet end of the chamber 26 is provided with a counterbore to receive a tubular valve seat member 27 which projects into the chamber 26. Surrounding and fitting the projecting end portion of this valve seat member 27 there is a tubular strainer member 28 within the valve chamber 26 and which is closed at its end adjacent the inlet 7. Within the strainer member 28 there is a valve member 29 cooperable with the valve seat member 27 to close the valve port 30 and to throttle flow therethrough. The valve member 29 has a longitudinal bore therethrough which receives a flexible operating rod or wire 31 which fits the valve member bore and is secured to the valve member by solder as at 31a which also seals the valve member bore. Closely adjacent and preferably at or in the wall 22, the bore of

the tubular member 23 on the outlet side of the valve seat member 29 has outlet ports 32, 33 leading into outlet conduits 34 (of which but one is shown in section) which have one side formed by the wall 22 and which receive the fittings 9, 10 respectively. The ports 32, 33 and the conduits 34 are in direct heat exchange contact with the wall 22 so that the temperature of the refrigerant medium leaving the valve is conducted directly to the casing 20. The bore 35 in the tubular member 23 extends into the internal portion 25 and is closed at its inner end by an end wall 36 having a central aperture therethrough through which the valve operating wire 31 extends. This end wall aperture is closed and sealed by a washer or packing member 37 within the bore 35 and having a tight sliding fit on the wire 31. The washer 37 is held against the end wall 36 by a helical coil spring 38 under compression and seating at one end on the washer and at its other end against the valve seat member 27. The wire 31 extends into the chamber 17 and has its end extending through a central aperture in a spring abutment member or disc 39. This wire end has a head 40 seating in a recess in the disc 39. The head 40 is held in the disc recess by a diaphragm reinforcing pad or plate 41, see Fig. 5 which is welded to the disc at a plurality of points such as indicated by the letter B. Surrounding the internal tubular member portion 25 there is a helical coil spring 42 which seats on the disc 39 and which is held under compression at its other end by an adjustable disc or abutment member 43 which is screw threaded on the portion 25. The edge of the disc 43 is serrated or toothed for cooperation with an adjusting pinion which is insertable into the chamber 17 through the opening 44 normally closed by the cap member 45. The diaphragm reinforcing pad 41 seats on a metal diaphragm 46 which is reinforced by a spider 47. The diaphragm and spider seat at their marginal edge portion on a downward facing annular shoulder 48 adjacent the rim of and in the casing side wall 21. The spider 47 is secured as by welding at its midpoint indicated by the letter A to a stop and supporting member 49 having an offset rim 50 engageable with a cap or cover member 51 which holds the diaphragm in position against the shoulder 48. The cap member 51 forms with the diaphragm 46 the sealed chamber 52 of the temperature responsive valve operating power element. The chambers 52 and 17 are simultaneously sealed and the diaphragm 46 and cap member 51 are sealed to each other and to the casing 20 by a single solder seal as at 53, the solder filling an annular chamber or recess at the rim edge of the diaphragm and between the cap member and the casing side wall 21. The cover or cap member 51 is provided with a filling or charging tube 54 which opens into the chamber 52 and by which the chamber 52 may be evacuated of air and charged with a suitable volatile liquid of such minute quantity that at some temperature above the operating range of the valve (which might be, say, 50° F. or 60° F. in a valve used in air conditioning), all of the liquid will be in vapor state thereby limiting the maximum pressure in the chamber 52 and acting on the diaphragm 46. The end wall 36 terminates closely adjacent the diaphragm so as to be engaged by the abutment disc 39 to limit the flexing of the diaphragm by the pressure within the chamber 52 and thereby serve as a stop and support to limit maximum diaphragm expansion.

The operation of the valve of Figs. 1 to 5 is as follows: The spring abutment disc 43 will have been adjusted to determine the superheat setting or operation of the valve so that the valve will close at a predetermined difference of temperature between the temperature of the refrigerant leaving the valve for supply to the evaporator and the temperature of the refrigerant leaving the evaporator. When the compressor 1 is started in operation, the reduction of pressure in the valve casing pressure chamber 17 will permit the diaphragm 46 to expand under the force of the vaporized liquid in the chamber 52 thereby moving the valve member 29 to open position. Refrigerant medium will therefore flow through the valve port and outlet ports 32, 33 and the outlet conduits 34 to the evaporators 13 and 14. As soon as the valve member 29 opens and admits refrigerant medium to the conduits 34, there will be a cooling of the casing 20 and a consequent withdrawal of heat from the power element chamber 52 thereby anticipating the flooding of the evaporators and causing the valve member 29 to be throttled or moved toward port closed position to reduce the rate of admission of the refrigerant to the evaporators. As a result of this anticipatory or compensated action by the valve the surging of the valve member and variation in the rate of refrigerant supply to the evaporators is materially reduced so that danger of flooding over of refrigerant medium into the chamber 17 is eliminated. Flooding over of refrigerant medium into the chamber 17 would cause complete closure of the valve member 29 with consequent starving of the evaporators and inefficient operation. In addition throttling of the valve member in anticipation of flooding of the evaporator permits substantially all of the evaporator to be utilized for refrigeration as distinguished from only a partial utilization of the entire length of the evaporators when surging occurs. When the temperature of the refrigerant medium in the chamber 17 decreases and approaches the superheat setting of the valve, then the pressure exerted by the vapor of the volatile liquid in the chamber 52 will decrease so as to permit the spring 42 to move the valve member 29 further toward closed position. The pressure in the power element chamber 52 will vary with the temperature of the vaporized refrigerant medium in the chamber 17 during the operation of the compressor and move the valve 29 toward open and closed position to regulate admission of refrigerant medium to the evaporators for maximum efficiency.

Referring to Figs. 7 to 10 inclusive, the valve 8 has a housing or body member including a cup-like casing 60 and a tubular member 61. The casing 60 is formed by stamping or drawing of a disc of sheet metal into the shape of a cup having a cylindrical side wall 62 with an annular internal shoulder 63 adjacent its rim or open end and having a bottom wall 64 which forms the upper end wall of the chamber 17. The wall 64 has a central depression or recess through which there is an aperture 65 receiving the tubular member 61. The tubular member 61 is provided with an annular shoulder which seats on the rim or marginal edge of aperture 65 and this joint is sealed and the members 60 and 61 are rigidly secured and sealed together by swaging of the material of the member 61 over upon the end wall 64 and by then solder sealing the joint. The outer or external face of the casing end wall 64 is provided with one or more radial recesses or grooves 66

extending from the central end wall recess. Alined with these recesses which are of partial cylindrical cross section, see Fig. 9 there are cylindrical recesses in the side wall of the tubular member 61. Accordingly, outlet tubes or conduits 67 will have side wall portions fitting the end wall grooves or recess 66 and have their ends extending into and fitting the tubular member recesses or sockets as at 68 which joints are sealed by solder. The contact between the conduits 67 and the end wall 64 is also a solder connection so that the conduits 67 are in direct and intimate heat exchange with the casing 60 and the end wall 64. The bore 69 of the tubular member 61 has within the external tubular member portion 70 an enlarged diameter bore portion 71 providing a valve chamber with its inlet provided with a conical strainer member 72. At the outlet end of the chamber 71 the bore 69 has a counterbore to receive a valve seat member 73. Cooperable with the valve seat member 73 there is a valve member 74 secured and sealed to a flexible operating rod or wire 75 all as described in connection with Figs. 1 to 5. The bore 69 on the outlet side of the valve seat member 73 has outlet ports 76 opening into the conduits 67. In this form of valve the helical coil spring 38 within the tubular member interior portion 25 does not seat against the valve seat member 73 but is held under compression by a separate sleeve member 77 press fitted within the bore 69 below the ports 76 which are between the sleeve member 77 and the valve seat member 73. Through the casing side wall 62 at diametrically opposite points directly underlying and parallel to the conduits 67 there are apertures which receive and have sealed therein an inlet fitting 78 and an outlet fitting 79 which are for connection to the suction line conduits 15 and 19, respectively so that the chamber 17 is intercalated in the suction line. The valve chamber 71 has an inlet fitting 30 by which the valve may be connected to the refrigerant liquid line or conduit 5. The remaining structure of this valve is substantially identical to that of the valve of Figs. 1 to 5, and therefore, the primes of reference characters applied to Figs. 1 to 5 will designate the like parts of this valve, Figs. 7 to 10. It may be noted however, that the spring abutment disc 43' has its serrated rim offset so that it alines with the suction line fittings 78 and 79 thereby eliminating the necessity for the aperture 44 since the disc 43' is adjustable through the suction line openings prior to installation of the valve. The operation of this valve of Figs. 7 to 10 will be apparent from the foregoing description of the valve of Figs. 1 to 5 when it is installed in the refrigeration system of Fig. 1.

In Fig. 6 the valve seat member 27 or 73 is shown as provided with a fixed by pass orifice or bleed 90 which is of such small size that it will not upset the control of the feeding of refrigerant medium by the valve when the compressor is in operation. However, this bleed will permit the pressure to equalize in the system during the off cycle or while the compressor is at rest and thereby provide an unloading means prior to the compressor being again placed in operation on the refrigerating cycle.

In Fig. 11 the tubular member interior portion 25 is provided with a calibrated bleed orifice 100 which discharges into the chamber 17 and against the valve operating diaphragm. Accordingly, when the valve member 29 opens some refrigerant medium will be supplied directly to the chamber 17 in passing relation to the evapora-

tors and increase the cold effect on and the abstraction of heat from the power element chamber 52. This will result in more quickly anticipating the flooding of the evaporators and in causing a greater extent of throttling of the valve member so as to still further reduce the rate of refrigerant medium to the evaporators.

It will be apparent that the by pass bleed or orifice 100 of Fig. 11 is equally applicable to either 10 of the valves above described. It will also be apparent that the bleed 90 of Fig. 6 can likewise be utilized with both of the described valves and can also be utilized with the by pass bleed 100 of Fig. 11.

15 Having thus described the invention, what is new and desired to be covered by Letters Patent of the United States is:

20 1. An expansion valve comprising a cup-like casing having an end wall and an opposite open side, a pressure responsive diaphragm closing and sealing said open side, a cap member sealed to said casing and to said diaphragm and forming with said diaphragm a temperature responsive pressure chamber, a volatile liquid in said chamber, said casing having inlet and outlet 25 openings for flow of vaporized refrigerant medium through said casing in contact with said diaphragm, a tubular member projecting externally from said end wall concentric with said diaphragm and having a longitudinal passageway therethrough opening into said casing, a valve seat member in said passageway, a valve member in said seat member, valve operating means extending through said passageway and said seat member and connecting said valve member to said diaphragm, said tubular member having an outlet from said passageway external of said casing, and means sealing said passageway around said 30 valve operating means on the casing side of said outlet.

35 2. An expansion valve comprising a cup-like casing having an end wall and an opposite open side, a pressure responsive member closing and sealing said open side, a cap member sealed to said casing and to said responsive member and forming with said responsive member a temperature responsive pressure chamber, a volatile liquid in said chamber, said casing having inlet and outlet openings for flow of vaporized refrigerant medium through said casing in contact with said responsive member, a tubular member projecting externally from said end wall concentric with said responsive member and having a longitudinal passageway therethrough opening into said casing, a valve seat member in said passageway, a valve member in said seat member, valve operating means extending through said passageway and said seat member and connecting said valve member to said responsive member, said tubular member having an outlet port from said passageway external of said casing, a conduit leading from said outlet port and having direct heat exchange contact with said casing end wall, and means sealing said passageway around said valve operating means on the casing side of said outlet.

40 3. An expansion valve comprising a cup-like casing having an open side, a tubular member having a longitudinal passageway therethrough transverse to the end wall of said casing and having inner and outer end portions projecting from opposite faces of said wall, said outer end portion having a passageway inlet and having a

laterally directed passageway outlet, a valve seat member in said passageway between said inlet and said outlet, a valve member in said passageway inlet and cooperable with said seat member, a diaphragm closing the open side of said casing, a reinforcing member movable with said diaphragm and interposed between said inner end portion and said diaphragm, a flexible wire extending through said passageway and operatively connecting said diaphragm to said valve member, said reinforcing member being engageable with said inner end portion to limit valve member movement, a cap member sealed to the open side of said casing and cooperating with said diaphragm to form a pressure chamber, a volatile liquid in said chamber operable on temperature increase to move said valve member toward said open position, said casing having inlet and outlet ports in its side wall and positioned between said end wall and said diaphragm for flow of refrigerant through said casing in contact with said diaphragm.

4. An expansion valve comprising a cup-like casing having an open side, a tubular member having a longitudinal passageway therethrough transverse to the end wall of said casing and having inner and outer end portions projecting from opposite faces of said wall, said outer end portion having a passageway inlet and having a laterally directed passageway outlet, a valve seat member in said passageway between said inlet and said outlet, a valve member in said passageway inlet and cooperable with said seat member, a diaphragm closing the open side of said casing, a flexible wire extending through said passageway and operatively connecting said diaphragm to said valve member, a sealing washer closing the inner end of said passageway and having a sliding fit on said wire, a helical coil spring held under compression by and between said seat member and said washer and holding said washer in passageway closing position, a cap member sealed to the open side of said casing and cooperating with said diaphragm to form a pressure chamber, a volatile liquid in said chamber operable on temperature increase to move said valve member toward open position, said casing having inlet and outlet ports in its side wall and positioned between said end wall and said diaphragm for flow of refrigerant through said casing in contact with said diaphragm.

5. An expansion valve comprising a cup-like casing having an open side, a tubular member having a longitudinal passageway therethrough transverse to the end wall of said casing and having inner and outer end portions projecting from opposite faces of said wall, said outer end portion having a passageway inlet and having a laterally directed passageway outlet, a valve seat member in said passageway between said inlet and said outlet, a valve member in said passageway inlet and cooperable with said seat member, a diaphragm closing the open side of said casing, a flexible wire extending through said passageway and operatively connecting said diaphragm to said valve member, a spring abutment member adjustable on said inner end portion, a helical coil spring held under compression by and between said abutment member and said reinforcing member and opposing movement of said valve member by said diaphragm, a cap member sealed to the open side of said casing and cooperating with said diaphragm to form a pressure chamber, a volatile liquid in said cham-

ber operable on temperature increase to move said valve member toward open position, said casing having inlet and outlet ports in its side wall and positioned between said end wall and said diaphragm for flow of refrigerant through said casing in contact with said diaphragm.

6. An expansion valve comprising a sheet metal cup having a central aperture through its end wall and having side wall apertures, conduit fittings secured and sealed in said side wall apertures, a tubular member extending through said central aperture and sealed therein, a diaphragm closing and sealing the open side of said cup, a sheet metal cap member sealed to said diaphragm and to said casing and forming with said diaphragm a temperature responsive pressure chamber, a volatile liquid in said chamber, said tubular member having a longitudinal passageway therethrough and having a cylindrical side wall recess external of said cup and communicating with said passageway, a conduit fitting secured and sealed in said side wall recess, valve means in said passageway on the inlet side of said recess, means extending through said passageway and operatively connecting said diaphragm to said valve means, and means closing the inner end of said passageway around said connecting means.

7. An expansion valve comprising a sheet metal cup having a central aperture through its end wall and having side wall apertures, metal tubing secured and sealed in said side wall apertures, a tubular member extending through said central aperture and sealed therein, a diaphragm closing and sealing the open side of said cup, a sheet metal cap member sealed to said diaphragm and to said casing and forming with said diaphragm a temperature responsive pressure chamber, a volatile liquid in said chamber, said tubular member having a longitudinal passageway therethrough and having a cylindrical side wall recess external of said cup and communicating with said passageway, said end wall having a radial recess aligned with said side wall recess, metal tubing secured in said radial recess and sealed in said side wall recess, valve means in said passageway on the inlet side of said recess, means extending through said passageway and operatively connecting said diaphragm to said valve means, and means closing the inner end of said passageway around said connecting means.

8. An expansion valve comprising a sheet metal cup having a central aperture through its end wall and having side wall apertures, conduit fittings secured and sealed in said side wall apertures, a tubular member extending through said central aperture and sealed therein, a diaphragm closing and sealing the open side of said cup, a sheet metal cap member sealed to said diaphragm and to said casing and forming with said diaphragm a temperature responsive pressure chamber, a volatile liquid in said chamber, said tubular member having a longitudinal passageway therethrough and having a cylindrical side wall recess external of said cup and communicating with said passageway, said tubular member having its inner end terminating adjacent said diaphragm to limit inward movement of said diaphragm, a spring surrounding said tubular member inner end and opposing inward movement of said diaphragm, a conduit fitting secured and sealed in said side wall recess, valve means in said passageway on the inlet side of said recess, means extending through said passageway and operatively connecting said diaphragm to said

valve means, and means closing the inner end of said passageway around said connecting means.

9. An expansion valve having an operating range in which it automatically throttles refrigerant medium flow, comprising a cup-like casing having an end wall and an opposite open side, a pressure responsive diaphragm closing and sealing said open side, a cap member sealed to said casing and to said diaphragm and forming with said diaphragm a temperature responsive pressure chamber, a minute quantity of fluid in said chamber and operable by condensation and vaporization in the operating range of the valve to actuate said diaphragm, said fluid being all in vapor state at a temperature above the operating range of the valve, said casing having inlet and outlet openings for flow of vaporized refrigerant medium through said casing in contact with said diaphragm, a tubular member projecting externally from said end wall concentric with said diaphragm and having a longitudinal passageway therethrough opening into said casing, a valve seat member in said passageway, a valve member in said passageway on the inlet side of said seat member, valve operating means extending through said passageway and said seat member and connecting said valve member to said diaphragm, said tubular member having an outlet from said passageway external of said casing, and means sealing said passageway around said valve operating means on the casing side of said outlet.

10. An expansion valve comprising a cup-like casing having an end wall and an opposite open side, a pressure responsive diaphragm closing and sealing said open side, a cap member sealed to said casing and to said diaphragm and forming with said diaphragm a temperature responsive pressure chamber, a volatile liquid in said chamber, said casing having inlet and outlet openings for flow of vaporized refrigerant medium through said casing in contact with said diaphragm, a tubular member projecting externally from said end wall concentric with said diaphragm and having a longitudinal passageway therethrough opening into said casing, a valve seat member in said passageway, a valve member in said passageway on the inlet side of said seat member, valve operating means extending through said passageway and said seat member and connecting said valve member to said diaphragm, said tubular member having an outlet from said passageway external of said casing, and means to bleed refrigerant medium from said passageway into said casing adjacent said diaphragm.

11. An expansion valve comprising a cup-like casing having an end wall and an opposite open side, a pressure responsive diaphragm closing and sealing said open side, a cap member sealed to said casing and to said diaphragm and forming with said diaphragm a temperature responsive pressure chamber, a volatile liquid in said chamber, said casing having inlet and outlet openings for flow of vaporized refrigerant medium through said casing in contact with said diaphragm, a tubular member projecting externally from said end wall concentric with said diaphragm and having a longitudinal passageway therethrough opening into said casing, a valve seat member in said passageway, a valve member in said passageway on the inlet side of said seat member, valve op-

10

erating means extending through said passageway and said seat member and connecting said valve member to said diaphragm, said tubular member having an outlet from said passageway external of said casing, means to bleed refrigerant medium from the inlet side to the outlet side of said seat member when said valve member is closed, and means sealing said passageway around said valve operating means on the casing side of said outlet.

12. An expansion valve comprising a cup-like casing having an end wall and an opposite open side, a pressure responsive member closing and sealing said open side, a cap member sealed to said casing and to said member and forming with said member a temperature responsive pressure chamber, a volatile liquid in said chamber, said casing having inlet and outlet openings for flow of vaporized refrigerant medium through said casing in contact with said member, a tubular member projecting externally from said end wall concentric with said member and having a longitudinal passageway with an inlet and an outlet external of said casing, a valve seat member in said passageway between said inlet and said outlet, a valve member in said passageway cooperable with said seat member, and valve operating means connecting said valve member to said pressure responsive member.

13. An expansion valve comprising a sheet metal cup having a central aperture through its end wall and having side wall apertures, conduit fittings secured and sealed in said side wall apertures, a tubular member extending through said central aperture and sealed therein, a pressure responsive member closing and sealing the open side of said cup, a sheet metal cap member sealed to said responsive member and to said casing and forming with said responsive member a temperature responsive pressure chamber, a volatile liquid in said chamber, said tubular member having a longitudinal passageway open at its end external of said cup and having a cylindrical side wall recess external of said cup and communicating with said passageway, a conduit fitting secured and sealed in said side wall recess, valve means in said passageway, and means operatively connecting said responsive member to said valve means.

14. An expansion valve comprising a stamped sheet metal cup having an outward facing shoulder adjacent its rim and having aligned side wall apertures, the end wall of said cup having a central aperture, metal tube fittings secured and sealed in said side wall apertures, a tubular member extending through and sealed in said central aperture and having a shoulder seating on said end wall, said tubular member having its end external of said cup open and having a side wall opening external of said cup, a metal tube fitting secured and sealed in said side wall opening, valve means in and controlling flow through said tubular member, a pressure responsive member seating on said shoulder and sealing the open side of said cup, a stamped sheet metal cap member seating on said responsive member and fitting said cup, means sealing said responsive member and said cap member to said cup, a volatile liquid in said cap member, and means operatively connecting said responsive member to said valve means.
